[57] CLAIM

The ornamental design for a level device, as shown and described.

DESCRIPTION

FIG. 1 is a top left front perspective view of a level device showing my new design;

FIG. 2 is a right side elevational view;

FIG. 3 is a front elevational view, the rear being a mirror image thereof;

FIG. 4 is a top plan view;

FIG. 5 is a bottom plan view;

FIG. 6 is a top left front perspective view of a second embodiment of FIG. 1;

FIG. 7 is a left side elevational view, the right side being a mirror image thereof;

FIG. 8 is a top plan view;

FIG. 9 is a front elevational view;

FIG. 10 is a rear elevational view;

FIG. 11 is a bottom plan view;

FIG. 12 is a top left front perspective view of a third embodiment of FIG. 1;

FIG. 13 is a left side elevational view, the right side being a mirror image thereof;

FIG. 14 is a top plan view;

FIG. 15 is a front elevational view;

FIG. 16 is a bottom plan view;

FIG. 17 is a rear elevational view;

FIG. 18 is a top left front perspective view of a fourth embodiment of FIG. 1;

FIG. 19 is a left side elevational view, the right side being a mirror image thereof;

FIG. 20 is a front elevational view;

FIG. 21 is a top plan view;

FIG. 22 is a bottom plan view;

FIG. 23 is a rear elevational view;

FIG. 24 is a top left front perspective view of a fifth embodiment of FIG. 1;

FIG. 25 is a left side elevational view, the right side being a mirror image thereof;

FIG. 26 is a front elevational view;

FIG. 27 is a top plan view;

FIG. 28 is a bottom plan view; and

FIG. 29 is a rear elevational view thereof.

The broken line showing of the bubble vial in the above figures is for environmental purposes only.
